UNITED STATES PATENT OFFICE.

MAX S. GOLDSMITH, OF CINCINNATI, OHIO.

CONCRETE FLOOR CONSTRUCTION.

Application filed November 23, 1921. Serial No. 517,851.

To all whom it may concern:

Be it known that I, MAX S. GOLDSMITH, a citizen of the United States of America, and resident of Cincinnati, in the county of Hamilton and State of Ohio, have invented a new and useful Improvement in Concrete Floor Constructions, of which the following is a specification.

This invention relates to improvements in concrete floor construction, especially that type wherein the ceiling is produced in a finished condition simultaneously with the moulding of the beams, cross beams and floor slabs.

15 An object of my invention is to produce a concrete floor construction in which the portion forming the ceiling consists of separately joined formed members embedded in the concrete of the beams and cross beams 20 and one surface of which may be finished to present a finished ceiling upon removal of the supporting frame work.

Another object is to provide an efficient and simple locking means for securing the 25 ceiling elements upon the concrete beams and upon one another.

Another object is to provide simple means to position domes upon the ceiling elements preparatory to pouring the plastic.

30 These and other objects are attained by the means described herein and disclosed in the accompanying drawings, in which:

Fig. 1 is a plan view of a number of ceiling plates showing their relation when positioned to have a plastic material poured thereupon.

Fig. 2 is an enlarged transverse sectional view taken on line 2—2 of Fig. 1.

Fig. 3 is a perspective view of a dome 40 forming a detail of my invention.

Fig. 4 is a plan view similar to Fig. 1 showing a modified form of construction.

Fig. 5 is an enlarged sectional view on line 5—5 of Fig. 4 and embodying certain 45 other modifications.

Fig. 6 is a perspective view of a ceiling plate or precast block forming a detail of my invention.

Figs. 7 and 8 are perspective views of 50 modified forms of precast blocks and means of forming seats for domes, all of which form details of my invention.

In constructing a floor embodying my invention, a series of rows of ceiling plates or 55 precast blocks 1, of any suitable material

are laid upon centering boards 2 forming a portion of the temporary form work 3, only the ends 4 of the blocks being supported on the boards with the ends and sides of the blocks abutting both longitudinally and transversely. At spaced intervals along each of the opposite ends 4, of the block are formed notches 5 which, on the upper surface 6 of the blocks, are of a smaller size than at the lower face or base 7 of said blocks, whereby an undercut face 8 extends between such upper and lower surfaces. These notches may be formed directly opposite one another upon the blocks, or the notches on opposite ends of the blocks 70 may bear a staggered relation if desired. When the notches are spaced directly opposite one another, as shown in Fig. 1, a cross sectional view taken to that portion of the block having the notches at opposite ends 75 thereof, discloses a substantially dove tailed form, as is shown in Fig. 6. In Figs. 4 and 6 the notches 5 are disposed at the corners of the blocks rather than intermediate the sides 80 as shown in Fig. 1. The plates are preferably made uniform so that the notches 5 of any one block will register with the notches of the adjacent block when the blocks are mounted upon the temporary structure 2 and 3, whereby, when a plastic material is poured upon the plates, some of the plastic will fill the pockets formed between adjacent plates and the temporary form work, thereby locking the plates upon such plastic material 85 after the plastic has hardened. The plates shown in Figs. 1, 2, 4, 5 and 6 have formed in their upper faces, the grooves 10 spaced at some slight distance from the notches 5 and extending substantially parallel with the ends of the blocks. These grooves are made 90 of sufficient width and depth to accommodate the lower edges 11 of the sides 12 of the domes 13, which are mounted upon the plates prior to the pouring of the plastic. The 95 domes may be provided with ends 14 which, together with the sides 12 and tops 15 thereof, serve to exclude any of the plastic from that portion of the plate covered by the domes. In the left hand portion of Fig. 1 is shown a construction wherein domes, such as shown in Fig. 3, are employed, and in which structure plastic is poured into the 100 spaces 16 between the ends of adjacent domes so as to form cross beams. In the right hand side of Fig. 1, the domes used have no ends 105

110

14, the adjacent domes overlapping one another as shown at 17, thereby eliminating the cross beams. When the concrete is poured so as to cover the plates and the domes, that which is disposed between the sides of adjacent domes, or in other words in the space 18, forms beams after it has hardened. That concrete which enters into the spaces 24 and 25, see Fig. 4, forms beams and cross beams 10 on hardening.

In Fig. 5 the groove 19 is formed upon the upper face of the plate by forming thereupon lugs 20 and 21 which extend substantially parallel of one another across the 15 upper face of the plate, the groove 19 lying between them.

In Fig. 7 the channel bars 26 are precast in the blocks, and the side plate 27 thereof extend upwardly from the upper surface 20 of the blocks and provide means to position the domes upon the blocks, the grooves in the blocks being dispensed with. The channel may be embedded in the block in any suitable manner, for example, the channel 25 may have wings 28 which are embedded in the block, or the channel may be set into the block, as shown in Figs. 7 and 8. The usual reinforcing bars 29 are placed between the domes. In pouring, the concrete 30 is worked into the pockets formed by the notches 5 and is caused to occupy the space between the sides of the domes so as to form beams and cross beams as explained. The pouring is continued until 35 the concrete is filled in and covers the tops of the domes to the required depth to form the floor slabs. Thus, after the concrete has hardened and the form work 2 and 3 has been removed, the ceiling plates will 40 be supported by the concrete keys 23 which were formed in the pockets occasioned by the notches 5. The plates or precast blocks form the ceiling for the story next below. If desired a plastic finish may be given to 45 the undersurface of the blocks.

The several blocks shown in Figs. 1, 2, 4, 5 and 6 are provided with notches 5 whereby same may be bound upon the concrete beams and cross beams. The undercut faces 50 formed on the blocks may be extended longitudinally and transversely of the blocks as shown in Fig. 4, or they may extend in but one direction as shown in Fig. 1. The ends of adjacent blocks may be spaced 55 instead of abutting, and the undercut surface extended the entire width of the blocks, as shown in Figs. 7 and 8, whereby a dovetailed concrete wedge is formed coextensive with the width of the blocks and which concrete wedge supports the adjacent blocks. 60

What I claim is:

1. In a concrete floor construction the combination of a series of ceiling plates having slots along their ends, the slots having undercut walls terminating upon the upper and lower faces of the plates, the slots of adjacent plates communicating, domes adapted to lie upon the upper faces of the plates, means on the upper faces of the plates adapted to position the domes 65 and for precluding spreading of the domes, and concrete surrounding the domes and filling the slots.

2. In a concrete floor construction the combination of a series of ceiling plates 75 having slots along their ends, the slots having undercut walls terminating upon the upper and lower faces of the plates, the plates having upon their upper faces ways extending in substantial parallelism with 80 the ends of the plates, arched forms adapted to have their lower ends disposed in engagement with the sides of the ways, the sides of the ways precluding spreading of the domes, and concrete surrounding the 85 forms and filling the slots.

3. In a concrete floor construction the combination of a series of ceiling plates having their ends and side edges in abutment upon one another and having registering notches along their edges, the walls of the notches receding inwardly and downwardly from the edges and tops respectively of the plates whereby openings are provided between abutting plates, the openings 90 being enlarged at their bottoms, arched forms mounted on the plates, and concrete surrounding the forms and filling the openings and having its lowermost surfaces 95 flush with the adjacent lower faces of the 100 plates.

4. In a concrete floor construction the combination of a series of ceiling plates having their end and side edges in abutment upon one another and having registering notches at their corners, the walls of the notches receding inwardly and downwardly from the tops of the plates whereby 105 openings are provided between abutting plates at the corners thereof, the openings 110 being larger at their bottoms than at their tops, and concrete extending over the plates and filling the openings and forming downwardly diverging keys supporting the plates.

In testimony whereof, I have hereunto 115 subscribed my name this 16 day of November, 1921.

MAX S. GOLDSMITH.
